UNITED STATES PATENT OFFICE.

DANIEL W. MILLSAPS, OF WASHINGTON, DISTRICT OF COLUMBIA.

DOOR SPRING.

1,405,735.

Specification of Letters Patent. Patented Feb. 7, 1922.

Application filed March 23, 1921. Serial No. 454,736.

To all whom it may concern:

Be it known that I, DANIEL W. MILLSAPS, a citizen of the United States, residing at Washington, District of Columbia, have invented certain new and useful Improvements in Door Springs, of which the following is a specification.

This invention relates to improvements in door closing devices and has for its object to provide a horizontally disposed spring connection between a door frame and door whereby the door will be normally held closed by said spring.

Another object of the invention is to provide a door and door frame having aligning bores, a coil spring mounted in said bores and connected to said door and frame, whereby the spring will draw the door closed when left open.

20 A still further object of the invention is to provide a simple coil spring connection between a door and door frame and means whereby said spring may be held connected to the door or released therefrom.

25 With the above and other objects in view, I have invented a device illustrated in the accompanying drawings, in which,

Figure 1 is an elevational view of the door and frame embracing my invention,

30 Figure 2 is a section on line 2—2 of Figure 1, and

Figure 3 is a detailed elevational view of a spring closure member.

Like reference characters indicate like parts throughout the following specification and in the several views of the drawings, in which 1 indicates a door frame, 2 a door hingedly connected thereto, 3 a bore in the frame aligning with a bore 4 in the edge 5 of said door. 6 is a coil spring having its end 7 fixed in the bore 3, the other end of which is adapted to normally seat in the bore 4 and is detachably connected therewith by means of a pin 8 operating through the opening 9 in the head 10 of said spring, said pin passing through the bore 11 in said door. The head 10 is provided with a rib 12 adapted to operate in a flaring groove 13 whereby the bore 9 is caused to align with bore 11. When the pin 8 is connected with the head 10 the spring will operate to close the door whenever it is opened and released. However, by disconnecting said pin 8 the

spring ceases to function and the door may be left open at will.

Having described my invention, that which I claim is new and desire to procure by Letters Patent is:

1. In combination with a door and frame having aligning bores, a spring seated in said bores and connected with the door and frame, whereby the door will be caused to normally close when released; means for disengaging one end of said spring whereby the door may be caused to remain ajar, said means consisting of a pin removably connected with said spring; a head on said spring having an opening to receive said pin, said door having a transverse bore and means whereby said opening is caused to align with said bore.

2. In combination with a door and frame members having aligning bores, a spring seated within both bores and having an end fixed to each member and means whereby one end may be disengaged from its members to permit said last end to seat disconnectedly in its bore, a head on said last end having a transverse bore adapted to align with similar bores in one of said members and a pin forming said last means, adapted to project through all of said transverse bores, and means whereby said transverse bores are caused to align, said last means including a pin on said head.

3. In combination with a door and frame members having aligning bores, a spring seated within both bores and having an end fixed to each member and means whereby one end may be disengaged from its members to permit said last end to seat disconnectedly in its bore, a head on said last end having a transverse bore adapted to align with similar bores in one of said members and a pin forming said last means, adapted to project through all of said transverse bores, and means whereby said transverse bores are caused to align, said last means consisting of a pin on said head, and a tapering groove forming a part of one of said first bores.

In testimony whereof I affix my signature in the presence of two witnesses.

DANIEL W. MILLSAPS.
